UNITED STATES PATENT OFFICE.

DANIEL H. REDMOND, OF PHILADELPHIA, PENNSYLVANIA, ADMINISTRATOR
OF DANIEL M. REDMOND, DECEASED.

OIL-HOLDER.

SPECIFICATION forming part of Letters Patent No. 554,308, dated February 11, 1896.

Application filed November 22, 1894. Serial No. 529,613. (No model.)

To all whom it may concern:

Be it known that DANIEL M. REDMOND, deceased, late a citizen of the United States, and a resident of the city of Philadelphia, in the county of Philadelphia and State of Pennsylvania, did in his lifetime invent certain new and useful Improvements in Oil-Holders, of which the following is a specification, furnished by me, DANIEL H. REDMOND, a citizen of the United States, residing at Philadelphia, Pennsylvania, administrator of the estate of said DANIEL M. REDMOND, deceased.

One object of the present invention is to provide an efficient, reliable and comparatively inexpensive holder for kerosene-oil, benzine, and other inflammable fluids, which is at all times filled, whereby the formation and collection of explosive gases are obviated, and in which there is no internal pressure, whereby danger of leakage is avoided; and to this end the invention consists of the improvements hereinafter described and claimed.

The nature, characteristic features, and scope of the invention will be more fully understood from the following description, taken in connection with the accompanying drawing, forming part hereof, and in which is illustrated partly in elevation and partly in central section an oil-holder embodying features of the invention.

In the drawing, 1 is a tank or vessel of any preferred size and shape, and in the example illustrated this vessel is located beneath the surface A B of the ground, and is provided with an oil-inlet 2 and an oil-offtake 3, both of which extend above the level of the ground, the latter not so far as the former. The oil-inlet 2 is or may be provided at its upper end with a stopper or stop-cock 4. The offtake 3 is provided with a stop-cock 5.

6 is a pipe or vessel that communicates with the interior of the tank or vessel 1, near the bottom thereof, and that is open at its upper end for the reception of a supply of fluid, as water, heavier than oil, issuing from the supply-pipe 7 and controlled by the stop-cock 8, and for the overflow of such fluid.

9 is a cup adapted to receive the overflow from the top of the pipe or vessel 6, and to lead the same away through the waste-pipe 10.

11 is a petcock or spigot located below the

upper end and communicating with the interior of the pipe 6, and also, in the present instance, bent around, as at 12, back of the pipe 6, so as to discharge into the waste-pipe 10. 55 13 is a hand-lever accessible from the ground and adapted to constitute means for opening and closing the petcock or spigot 11.

The mode of operation of the above-described apparatus is as follows: The tank or vessel 1 is filled with oil, benzine or other inflammable material, for example, level with the petcock 11. For this purpose the petcock 11 may be opened and the oil, benzine or other inflammable material poured into 65 the inlet 2 until it appears at the petcock. During this operation the supply-pipe 7 is closed by means of the valve 8. The petcock 11 is then closed and water is permitted to escape from the supply-pipe 7 and to collect 70 in the vessel or pipe 6. The weight of the water in the vessel 6 displaces the lighter oil, benzine or other inflammable material and causes it to rise in and fill the vessel or tank 1, until finally a state of equilibrium between 75 the two liquids is established. For example, the oil rises to the level indicated by the line a b, and the water rises to the level indicated by the line c d. Under these circumstances the weight of the columns of oil and water 80 balance each other, so that additional water leaving the supply-pipe 7 overflows from the pipe 6 into the cup 9, and thus escapes from the waste-pipe 10. However, when the cock 5 is opened oil flows from it by reason of the 85 fact that the level of the oil a b is above it, and the space which was occupied by the oil so drawn off is immediately filled with water that flows in through the pipe or vessel 6.

From the foregoing description it will be obvious that the vessel 1 is always full, so that there are no spaces in which explosive gases, vapors and the like can collect, and that since the oil simply remains supernatant or floating upon the water the apparatus is not subjected to internal pressure, whereby leakage and its consequent dangers are avoided. When all the oil has been drawn off the vessel 1 is, of course, filled with water. However, this water is expelled during the refilling operation above described by reason of the fact that the petcock 11 is open, thus re-

ducing the height of the water column, and the inlet 2 is filled to its top with oil, thus increasing the height of the oil column. By increasing the height of the top of the pipe 6 5 the weight of the column of heavier fluid, as water, is increased, so that the level *a b* of the lighter fluid, as oil, may be raised, thus permitting the stop-cock 5 and offtake 3 to be placed farther above the ground-line A B.

10 The absence of internal pressure in the vessel 1 permits of the use of a float 14 and index-rod 15, that is attached to the float and works in a tube 16, projecting upward from the vessel 1, as shown. This float 14 is so 15 weighted or loaded as that it floats on water and sinks in oil, and thus rises and falls as the line *c d* rises and falls, and consequently causes the index-rod 15 to indicate the quantity of oil contained in the vessel 1. 17 is a 20 cap that may be used for covering the upper end of the tube 16, as required.

It will be obvious to those skilled in the art to which the invention relates that modifications may be made in details without departing 25 from the spirit thereof. Hence it should not be limited to the precise construction and arrangement of parts hereinabove set forth

and illustrated in the accompanying drawings; but,

Having thus described the nature and objects of the invention of the said DANIEL M. REDMOND, deceased, what I, his administrator, claim as new, and desire to secure by Letters Patent, is—

The combination in an oil-holder, with an 35 oil-vessel closed at its top, an immovable pipe open at its upper end and communicating with the lower portion of said vessel at its other end and provided intermediate of its ends with a petcock, and means for introducing water into the open end of said pipe, of a cup provided with a waste-pipe and containing said petcock and underlying the open end of the fixed pipe, an oil-offtake, and an oil-inlet, substantially as described. 40

In testimony whereof I have hereunto signed my name.

DANIEL H. REDMOND,
Administrator of the Estate of Daniel M. Redmond.

In presence of—
EVAN J. LESTER,
A. B. STOUGHTON.
